UNITED STATES PATENT OFFICE

2,188,851

REFRIGERATOR CAR FLOOR RACK

Charles David Bonsall, Pittsburgh, Pa., assignor to Standard Railway Equipment Manufacturing Company, Chicago, Ill., a corporation of Delaware

Application December 20, 1937, Serial No. 180,705

5 Claims. (Cl. 105—375)

The invention relates to insulated refrigerator cars used to transport perishable commodities, such as vegetables, fruits, berries, meats, eggs, frozen fish, etc., and to maintain such commodities while in transit within a predetermined range of temperature, thus necessitating the use of a cooling means in the summer and a heating means in the winter. It has been found that perishable commodities which have not been allowed to get too cold (freeze) or too hot (bake) have a high market value because they have a longer storage life.

The object of the invention is to provide a floor rack comprising a metallic plate shaped to form a plurality of beam structures (with air channels therebetween) which are supported in spaced relation to the insulated floor of the car by insulating members and a foraminous metallic sheet secured to such beam structures for supporting a lading thereupon.

The object of the invention is to provide a floor rack for a refrigerator car which is very strong to support vertical loads and has great strength in a horizontal direction (to resist the tendency of a shifting load to move the floor rack sidewise) without materially retarding the flow of air below the floor rack or materially reducing the amount of air flow through the floor rack.

In the drawings:

Fig. 1 and 2 show the corelation of my device to the other elements of a refrigerator car.

Fig. 3 shows a plan view of my improved floor rack.

Fig. 4 is an enlarged cross section of a part of floor rack.

Fig. 5 shows a detail of construction.

Fig. 6 shows a perspective view of part of my floor rack.

In the form of my invention illustrated the refrigerator car is provided with a bulkhead 2 separating the refrigerant chamber 3 from the lading compartment 4. The bulkhead 2 is provided with an aperture 5 adjacent the floor 6 of the car and an aperture 7 adjacent the ceiling 8 of the car with a solid wall 9 therebetween.

A refrigerant is supported by the grates 12 in the refrigerant chamber 3 in spaced relation to the floor 6 of the car and the basket (or netting) 13 spaces the refrigerant from the end wall 14 and bulkhead 2 to provide the flues 16—17. The apertured floor rack 18 supports the lading so as to provide the space or flue 20 which communicates with the flues 16—17. A refrigerant, such as ice, in the refrigerant chamber induces a convection circulation of air from

the flues 16—17 through the flue space 20 under the floor rack which rests upon the floor 6. The air permeates upwardly through the rack, which is foraminous, and as it is warmed by the lading, it rises and passes through the bulkhead upper opening 7, and thence through the flues 16—17, and being cooled by the refrigerant, repeats the convection cycle.

My improved floor rack comprises a metallic plate 30 formed with upper portions 32 and lower portions 34 in spaced apart substantially parallel planes preferably connected by perforated (35) webs 36 which are preferably diagonally disposed and a foraminous floor 38 extending between the upper portions 32 of the metallic plate and secured thereto (40). Such a construction provides flues 42 for circulating air below the upper portions 32 and flues 44 above the lower portions 34, which flues extend in the direction of the movement of the air current. Such a construction provides a very strong floor rack to support the lading and the impact thereof as well as to resist the tendency of the load to shift in various directions in a horizontal plane.

In the form of invention shown the foraminous floor comprises a metallic sheet 38 resting upon and secured to the upper portions 32 of the metallic plate, which sheet is formed with a plurality of upwardly projecting panels 48 extending between the adjacent upper portions 32 to provide reinforcing beams therebetween. The panels are provided with apertures 50 for air circulation therethrough, which apertures 50 are provided with a peripheral depending stiffening flange 52. The upper surface of the panels 48 are preferably flush with or above the heads of the rivets 40 which secure the metallic sheet 38 to the metallic plate 30 so as to provide an even surface for the lading in the car.

The modern floor rack is hinged (54) to a vertical wall 56 of the car so it may be raised to a substantially vertical position to clean the insulated floor of the car, therefore, I preferably provide a rod 58 extending through and secured to a plurality of webs 36 to strengthen the rack while it is being raised or lowered (see Fig. 5).

I preferably provide insulating members 60 secured (62) to the lower portions 34 of the metallic plate and supporting such lower portions upon the floor 6 of the car and spaced therefrom. In the drawings I have shown a plurality of spaced apart wooden insulating blocks 60 staggered and secured to each lower portion of the metallic plate. Such insulating blocks re-

tard heat transfer through the floor rack and also provide means of adjustability for the height of the floor rack. They have the further advantage that they will not wear into the asphalt composition (which usually covers an insulated floor of a refrigerator car) as rapidly as the metallic plate.

It will be noted that the circulating air may move freely around and between the insulating blocks and also pass freely through the various webs and apertures in the metallic sheet.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

- 20 1. In a refrigerator car having a floor, a rack for supporting a lading in spaced relation to said floor to provide a flue therebetween and means to induce an air current in said flue, said rack comprising a metallic plate formed with upper portions and lower portions in spaced apart substantially parallel planes connected by perforated webs to provide flues below the upper portions and above the lower portions extending in the direction of the movement of said air current, and a foraminous floor extending between said upper portions and secured thereto.
- 25 2. In a refrigerator car having a floor, a rack for supporting a lading in spaced relation to said floor to provide a flue therebetween and means to induce an air current in said flue, said rack comprising a metallic plate formed with upper portions and lower portions in spaced apart substantially parallel planes connected by perforated webs to provide flues below the upper portions and above the lower portions extending in the direction of the movement of said air cur-

rent, a foraminous floor extending between said upper portions and secured thereto, and insulating members secured to the lower portions of the metallic plate and supporting said lower portions upon the floor of the car.

3. In a refrigerator car having a floor, a rack for supporting a lading in spaced relation to said floor to provide a flue therebetween and means to induce an air current in said flue, said rack comprising a metallic plate formed with upper portions and lower portions in spaced apart substantially parallel planes connected by perforated webs to provide flues below the upper portions and above the lower portions extending in the direction of the movement of said air current, and a metallic sheet resting upon and secured to said upper portions, said sheet being formed with a plurality of upwardly projecting panels extending between and terminating at adjacent upper portions which are provided with apertures for air circulation therethrough.

4. In a refrigerator car having a floor, a rack for supporting a lading in spaced relation to said floor to provide a flue therebetween and means to induce an air current in said flue, said rack comprising a metallic plate formed with upper portions and lower portions in spaced apart substantially parallel planes connected by perforated webs to provide flues below the upper portions and above the lower portions extending in the direction of the movement of said air current, a foraminous floor extending between said upper portions and secured thereto, and a plurality of spaced apart wooden insulating blocks secured to each lower portion of the metallic plate.

5. A structure as defined in claim 1 including a rod spaced below said foraminous floor, said rod extending through and secured to a plurality of said webs for the purposes specified.

CHARLES DAVID BONSALL.
